(57) **CLAIM**

The ornamental design for an automobile upper front bumper, as shown and described.

DESCRIPTION

FIG. 1 is a front perspective view of an automobile upper front bumper attached to a vehicle, no part of the vehicle is claimed;

FIG. 2 is a perspective view of the automobile upper front bumper;

FIG. 3 is a front elevational view of the automobile upper front bumper;

FIG. 4 is a top plan view of the automobile upper front bumper;

FIG. 5 is bottom plan view of the automobile upper front bumper; and,

FIG. 6 is a right side elevational view of the automobile upper front bumper (the left side view is a mirror of the right side view and is not shown).

The broken lines are for illustrative purposes only and form no part of the claimed design.
